COMBINED HANDBAG AND UMBRELLA HOLDER

Phillip Kates, Queens County, N. Y.

Application March 31, 1955, Serial No. 35,297

Term of patent 14 years

(Cl. D87—3)

FIG. 1.

FIG. 2.

Fig. 1 is a perspective view showing the top, front and one side of a combined handbag and umbrella holder embodying my new design, and

Fig. 2 is a perspective view showing the bottom, rear and other side of my design.

The broken lines showing the umbrella is for the purpose of illustration only.

I claim:

The ornamental design for a combined handbag and umbrella holder, as shown and described.
